United States Patent Office.

CHARLES BUNGER, OF NEW HAVEN, CONNECTICUT.

Letters Patent No. 65,722, dated June 11, 1867.

MATCH-SAFE.

The Schedule referred to in these Letters Patent and making part of the same.

TO ALL WHOM IT MAY CONCERN:

Be it known that I, CHARLES BUNGER, of New Haven, in the county of New Haven, and State of Connecticut, have invented a new improvement in Match-Safes; and I do hereby declare the following, when taken in connection with the accompanying drawings, and the letters of reference marked thereon, to be a full, clear, and exact description of the same, and which said drawings constitute part of this specification, and represent, in—

Figure 1, a perspective view; and in

Figure 2, a section on line xx .

This invention relates to an improvement in the construction of a receptacle for matches, and consists in the peculiar construction whereby a single match is at all times in position to be removed, and so that but one match at a time can be removed.

To enable others to construct my improvement, I will proceed to a description of the same as illustrated in the accompanying drawings.

A is the back of the safe or case, and may be formed so as to be attached to the wall or any convenient position in any convenient or known manner. B, the bottom of the case, is made inclined downward from the back, its front edge C turned up so as to form a trough, D, between the turned-up part C and the front E of the case, as clearly seen in fig. 2. Near the centre of the said trough, and through the front E, I cut a recess, as seen in fig. 1, and provide the case with a cover or not, as may be deemed advisable. The front of the case E extends down so near to the bottom as to leave a space only sufficiently large for a single match to pass into the trough, therefore when the matches in quantity are placed within the receptacle, one passes through the said space into the trough and there lies until removed, and is removed by taking it between the thumb and finger in the space formed in the trough, and when so removed a second match follows it into the trough, and so on until all the matches have been one by one removed.

I do not broadly claim a match-safe provided with an opening in its bottom through which the matches are delivered.

Having therefore thus fully described my invention, what I claim as new and useful, and desire to secure by Letters Patent, is—

The match-safe, constructed substantially as herein described, provided with an inclined bottom, B, and the trough D, into which an opening through the front permits a single match to enter the said trough, and constructed so as to remove the match from the said trough, substantially as and for the purpose specified.

CHARLES BUNGER.
